AUTOMATIC REGULATOR FOR INCUBATORS

Filed March 18, 1929

UNITED STATES PATENT OFFICE

FRANK S. MCKIBBEN, OF CHULA VISTA, CALIFORNIA

AUTOMATIC REGULATOR FOR INCUBATORS

Application filed March 18, 1929. Serial No. 347,921.

The object is to provide a regulator that will automatically maintain a good hatching temperature for twenty-four hours, the temperature produced being not more than 103 degrees at any time in a room temperature of about 100 degrees and not less than 102 degrees in a room temperature of about 50 degrees. Incidentally a further object is a considerable saving of oil. These limits 10 may be changed at the factory but not elsewhere.

The invention consists essentially, of a sleeve arranged for a sliding movement upon the wick tube of the lamp, and adapted to provide means for automatic adjustment of the size of the flame to make it very large or very small as needed and to prevent complete extinguishment. Rising of the sleeve lowers the flame and vice versa.

In the further description, reference is made to the drawings herewith in which like numerals refer to like parts throughout. Figure 1 is a front elevational view of the regulator mounted in operative position upon an incubator. All of the parts are shown but some are partly broken away. Figure 2 is an end elevational view with the burner and flue of the lamp shown partially in section. Figure 3 is a perspective of the adjusting stops piece which is shown in front elevation in Figure 1. A thermostat 1 of any desired type is mounted upon a stirrup or bracket 2 by means of the screw 3 and is thus attached to the top of the incubator. An upright rod 4 rests upon the top of the thermostat and passes through a hole 5 in the top of the incubator and is there connected with other operative parts above. A fulcrum support 6 for the primary lever 7 is attached to the top of the incubator near the hole. One end of the primary lever is fulcrumed on this support. The lever extends toward and nearly to the lamp and in its under side near the fulcrum, a shallow socket is formed to receive the upper end of the rod 4. The socket divides the lever into two very unequal arms so that its free end moves twenty or thirty times as far as the rod moves.

The support 8 for the fulcrum 9 of the secondary lever 10 is attached to the top of

the incubator directly under the primary lever and close to its free end. The free end of the primary lever is connected to the secondary lever about half an inch from its fulcrum by means of the flattened ring or link 11. The upper end of the link rests in a notch in the upper edge and near the end of the primary lever. There is a notch 12 in the under edge of the secondary lever about half an inch from its fulcrum 9. The lever 10 passes through the opening of the link and the notch 12 rests on the inner side of the lower end of the link. Notches are not a necessity and in some places, other forms of connections will be preferable. The fulcrum 65 should be loose in its bearings. For economy in making, the secondary lever with fulcrum attached may be cut from sheet metal in one piece and bent to proper shape. It is eight or ten inches long with the fulcrum near the 70 middle, though the exact location is not important. The secondary lever extends to a point a little beyond the extended central line of the flue 13. It ends in an incline 14 which will be convenient for the daily assembling or making the daily pilot flame. Close to the incline there is a small notch 15 in the upper edge of the secondary lever 10 which engages a similar notch 16 in the under edge of the top horizontal part 16a of the 75 hanger.

The hanger is for the purpose of transmitting exact movements from the secondary lever 10 to the sleeve without passing down through the flue by holding the sleeve a definite and constant vertical distance from the lever. For the sake of uniformity, rigidity and low cost the hanger may be cut in one piece from sheet metal by a die. It is in the form of a frame consisting of three parts. A 85 top part 16a is disposed horizontally across the secondary lever 10 near its end, their respective notches engaging each other to prevent slipping. The part 16b is disposed horizontally to operate on the level of the burner. A third part 16c is disposed vertically outside of the boiler and flue 13 so as to unite the parts 16a and 16b at their left hand ends. The right hand end of the latter overlaps the sleeve and is brazed to it. As the object of the brazing is 90 95 100

to hold the sleeve always in the same position as related to the hanger, the attachment may be made by means of any latch or other holder that will thus hold the sleeve fixedly for operative purposes and yet may be removed and replaced at will. The sleeve is mounted slidably on the wick tube 18 which acts as a guideway. The sleeve by these connections, is adapted to swing freely from the lever 10 and to follow its vertical movements as the lever rises by the force of the expanding thermostat and falls by the force of gravity as the thermostat cools. The burner in common use may be used, but I prefer certain modifications. The usual perforated disc which forms the floor of the burner is very liable to interfere with the movements of the sleeve whose lowest position should be almost touching the crowned top of the star wheel chamber. Therefore, the disc should not be used. The body of the burner below the cap is a hollow cylinder or shell 20 which is closed at its top by the cap. The bottom is also closed and screws into the lamp bowl. The sides of the cylinder are perforated to admit air and yet to protect the flame from air drafts. A deep, narrow notch 21 extends through the thickness of the shell from its top almost to its bottom. The lower part of the hanger, 16b, passes through this notch for actuating the sleeve. I make no claim in reference to the burner, but merely indicate how the well known burner should be modified for my purposes. It may be seen by inspecting Figure 2 that a greater part of the weight of the hanger is on the left side of the lever 10. This causes a tendency for the sleeve to swing to the right and rub against the wick tube making more or less objectionable friction. To correct this tendency, a small weight 19 is attached to the part 16a of the hanger to the right of the lever 10. The weight is to be adjusted to bring the center of the sleeve to the center of the wick tube. But a small amount of unavoidable friction will not be noticeable. Therefore, with previous careful experiment the hanger may be cut in one piece with sufficient accuracy that a separate weight and later adjustment will not be needed.

In the operation of this regulator, the weight of the hanger and sleeve, indirectly suspended from the end of the primary lever and the weight of the lever itself must be raised by the thermostatic expansion under the disadvantage of great leverage. This would require, with the usual mechanism, a much stronger thermostat and the greater friction would retard the movements of the sleeve. Most of the weight can be counterbalanced by a weight on the further end of the primary lever 7. But at present I prefer to do this by means of a spring 22 which at one end is attached to the top of the incubator, is bent over and, at the other end is inserted

under the primary lever near its end. The adjustment of the spring will be described later.

A principal feature of my invention is shown in Figures 1 and 3. It is a single piece cut by a die from sheet metal and bent to desired shape. A base plate 23 serves to fasten the piece to the top of the incubator. A frame 24 set on edge is continuous along its lower edge, with the base plate and two tables 25 and 26 are continuous along one end of each with the frame. The tables are bent nearly to a horizontal position to form stops, one above and one below, between which the further end of the secondary lever 10 oscillates at irregular intervals according to temperature. The tables are about three eighths of an inch apart plus the vertical thickness of the lever, provided the fulcrum is at the middle of the lever and provided the sleeve must rise three eighths of an inch above its lowest position to make a pilot flame which is usual for a number 2 wick. To make the tables operative and effective stops, they must be adjusted. This may be quickly done in connection with the spring 22 already partially described.

For adjusting the spring and the table 25 a temperature of 102 degrees is required. This will be understood when the construction and operation of the invention have been further considered. The heat required for the adjustments may be supplied by a lamp but when there is a considerable number of incubators to be made, it will doubtless be found much more economical to heat by a specially designed apparatus using steam or hot water. But herein the adjustments will be described as made with a lamp as an illustration. The lamp must be fitted with a temporary stop that may be made in a convenient way that will prevent the sleeve from going higher than its lowest position and not interfere with the flame. There are several ways of making such a stop and one that is applied to the top of the hanger will be good and economical. But further description herein will hardly be in place.

The fully equipped and lighted lamp is put in place against the bottom of the flue and held by a shelf or lamp holder having a suitable latch to draw the burner snugly up against the flue and drop down out of the way when it is loosened. When the temperature is at 102 degrees, the sleeve is raised only a very little, up against the temporary stop, its top being thus made level with the top of the wick tube, its lowest position. The raising must be done by means of the screw 3 so as to put all parts under the same strain that will be upon them in operation. The screw is to be turned by means of a pair of pliers or a special tool applied to the rod 4 just below the primary lever 7. While the sleeve is thus held in its lowest position, the

table 25 is bent down to make contact without pressure with the secondary lever 10. In operation this contact will prevent the sleeve from going lower than its lowest position so 5 that afterward, a slightly upward movement of it will have an immediate effect in partially reducing the size of the flame thus making the device more sensitive. This adjustment also establishes a base upon which 10 other adjustments are made. Also, in operation this contact continues, making a full flame that is not affected by any lower temperature, till the temperature rises a little above 102 degrees, after which the rising 15 temperature causes the sleeve to rise rapidly to make a pilot flame at 103 degrees and during the same time the further end of the lever 10 is lowered away from the table stop 25 toward the table stop 26.

20 After the adjustment of the table stop 25 the temperature is carefully raised to 103 degrees. This temperature is essential for adjusting the table stop 26 though not so important for the adjustment of the spring 25 which is adjusted by bending it to make slight upward pressure on the lever when the temperature is right. The spring should be made of proper tension to allow the sleeve to go to its lowest position promptly but not 30 with force when the temperature declines to 102 degrees. When the temperature rises to 103 degrees after the adjustment of the stop 25 the sleeve should be raised three eighths of an inch above its lowest position and while it 35 is held at that the stop 26 should be bent up to make contact without pressure with the lever 10. The sleeve must be raised by means of the screw, as before and for the same reason. After the adjustments, a pilot flame 40 will be made automatically whenever the temperature reaches 103 degrees, provided the daily pilot flame shall have been made as described later on and provided the distance, three eighths of an inch, has been experimentally 45 found to be correct for wicks of the same size that is used. When the sleeve is raised to its proper highest position, a mark or stop placed on the temporary stop will be a reliable and convenient gage to be used in all 50 future regulators using the same size of wicks, whether heated by a lamp or otherwise. It will be noted that the flame is not used for making adjustments but for heating. However, there is another way, equally good, 55 for adjusting by means of the flame.

50 All the foregoing specifications refer to manufacturing, assembling and adjusting in the factory. The ultimate user and owner will not be interested in them and they should 60 never be changed. The only one of such things in which the user will be interested will be the making of the daily pilot flame. There is but one way to start and operate this regulator and that is to make a daily pilot 65 flame. Every time after the flame has been

extinguished for cleaning and filling or for any other purpose. It takes only two or three minutes. It is made thus: The lamp, filled and cleaned, is placed on a table. The burner cap is removed or turned back on its hinge. 70 The sleeve, with the hanger attached, is lowered upon the wick tube, the lower part 16b of the hanger entering the deep narrow notch 21 leaving the part 16c upright. The cap is put in place. Now the lamp is lighted and 75 turned low and raised up to put the burner against the flue. While one hand holds the lamp, the other raises the lamp shelf or holder up against the bottom of the lamp and latches it so as to draw the burner snugly 80 against the flue. The upper part of the hanger is now slipped over the incline at the end of the lever 10 into the notch being careful not to lift the hanger for doing so might extinguish the flame unless it is first turned 85 high enough to burn the fingers. A folded cotton rag will protect the fingers.

With a left finger under the end of the lever 7 raise the sleeve as far as it will go, that is, till the further end of the lever 10 goes down 90 and strikes the stop 26. But while this is being done, the flame must be watched and turned up by the right thumb and finger on the wick wheel so as to prevent extinguishment. While the sleeve is thus held in its high 95 position, the flame is turned higher or lower to make the smallest flame that will continue to burn and not go out. This is the daily pilot flame. Let the levers down. Though the flame will be large at first, it will 100 be under the complete control of the thermostat. Afterward the pilot flame will return automatically whenever the temperature rises to 103 degrees and the temperature will seldom be less than 102 degrees if the room temperature is good for comfortable living, that is, from 60 to 100 degrees. A thermometer cannot be used to regulate the temperature while this regulator is working. But, if the user wants to try the old way, he can easily 105 do so by neglecting to make the daily pilot flame and then using a thermometer. He can, at any time, return to the automatic regulation by making a daily pilot flame. Even for knowing sufficiently the temperature 110 of the room, a thermometer is not needed. When the pilot flame continues more than five or ten minutes at a time, the room is near the danger point and should be cooled by familiar procedure. If the flame remains 115 full size more than five or ten minutes at a time, the room is too cold, fifty-five degrees, or less and should be heated by any convenient fire.

The details of construction, et cetera, as 120 mentioned, though true and complete, are not given so much for definite and unchangeable instruction as for suggestions and explanation to be followed or not by a manufacturer after he has made a study of them for him. 125

self. Also, for the most part, the methods of assembling and adjusting are described for the purpose of suggestion and illustration rather than as fixed rules, for in many respects, other plans will be good or better economically, though the operative results are so nearly perfect that improvement is hardly possible. The statements made in reference to the operation of this regulator and purporting to be facts are not theoretical speculations but have resulted from long and careful observation and experiment with a real incubator in reel incubation repeated several times and always with excellent results.

Having thus described my invention, I claim as new:

1. In temperature control means for an incubator, the combination with a heating lamp having a wick tube, a flue and a flame control sleeve slidably mounted on said tube, a control thermostat and a lever actuated by said thermostat, the free end of said lever extending to a point directly over said flue, of means outside the flue for operatively connecting the free end of said lever to the sleeve.

2. In temperature control means for an incubator, the combination with a heating lamp having a wick tube, a flue and a flame control sleeve slidably mounted on said tube, a control thermostat and a lever actuated by said thermostat, the free end of said lever extending to a point directly over said flue, of means outside the flue for operatively connecting the free end of said lever to the sleeve, said means comprising a U-shaped hanger.

3. In temperature control means for an incubator, the combination with a heating lamp having a wick tube, a flue and a flame control sleeve slidably mounted on said tube, a control thermostat and a lever actuated by said thermostat, the free end of said lever extending to a point directly over said flue, of means outside the flue for operatively connecting the free end of said lever to the sleeve, said means comprising a U-shaped hanger having two horizontal legs, an upper one being disposed crosswise to be actuated by said lever and a lower one disposed so as to be attached to said sleeve for actuating it.

FRANK S. MCKIBBEN.
